(57) **CLAIM**

The ornamental design for a goose neck faucet, as shown and described.

DESCRIPTION

FIG. 1 is an upper perspective view of a goose neck faucet showing my new design;

FIG. 2 is a side view thereof;

FIG. 3 is an opposite side view thereof;

FIG. 4 is a front view thereof;

FIG. 5 is a rear view thereof;

FIG. 6 is a top plan view thereof; and,

FIG. 7 is a bottom plan view thereof.

The broken lines in FIGS. 4 and 7 illustrate portions of the goose neck faucet that form no part of the claimed design.
